MECHANICAL TIME FUSE HAVING A CENTRIFUGAL DRIVE

Helmut Junghans, Schramberg-Sulgen, Germany

Application November 11, 1936, Serial No. 110,355
In Germany July 27, 1935

5 Claims. (Cl. 102—36)

The invention relates to mechanical time fuses having a centrifugal drive.

The primary object of the invention is to provide an operating means for time fuses of the kind in question having a comparatively long period of operation, whereby the said operating means, whilst supplying a sufficient force, does not appreciably exceed in its dimensions, and more particularly in its diameter, the dimensions of existing operating devices.

A further object of the invention is to provide an operating means of this nature in extremely simple form.

Mechanical clock-work fuses have already been proposed, in which a pair of centrifugal weights are disposed symmetrically to the central shaft of the fuse, each of the said weights acting on the shaft by way of an intermediate wheel. There is accordingly provided on each cover plate of the clockwork mechanism a centrifugal weight together with its appertaining transmission wheel. For the purpose of increasing the operative force and for varying the transmission ratio to produce a slower operation in the case of an operating means composed of substantially the same parts, these parts in accordance with the invention are constructed and arranged as follows:

Each of the centrifugal elements disposed symmetrically to the axis of the fuse as a pair drives a transmission wheel acting on the central shaft of the fuse, which transmission wheel in turn is mounted about the axis of rotation of the opposite centrifugal member. This arrangement leads to a considerable saving in space, which may be utilized for increasing the mass of the centrifugal weights and the extent of their swinging movement.

According to an additional feature of the invention, the intermediate wheels in turn are constructed and arranged in the manner of centrifugal weights, for example in the form of toothed segments. To simplify the construction of the operating mechanism there is employed in each case as bearing bolt for a centrifugal weight and an intermediate wheel one of the threaded bolts which hold together the cover plates of the clockwork mechanism. For the additional saving of space, in accordance with the invention, use is made at a suitable point, for example on the central wheel, of inner teeth. A device constructed on these lines is particularly adapted to replace an operating device having a short period of operation, whilst the actual movement between the balance and the wheel on the central shaft, with a view to simplifying the manufac-

ture of fuses having different periods of operation, may always remain the same.

Additional objects and advantages of the invention will become apparent from the following description.

A possible form of embodiment of the invention is illustrated by way of example in the accompanying drawing, in which

Fig. 1 is a section taken through the central axis of a fuse.

Fig. 2 is a plan view of the fuse, the upper cover plate having been removed to reveal the centrifugal weights.

Fig. 3 is a plan view of the fuse in which the upper cover plate and the centrifugal weights have been removed to reveal the intermediate segments.

In the embodiment illustrated in the drawing there is shown a construction in which the object was to double the time of operation of an existing operating device, viz., from 60 to 120 seconds. A condition is that the dimensions of the operating device, and more particularly the diameter, do not appreciably exceed the dimensions of the previous device, and further that the new operating device is so adapted from the point of view of construction to the previous mechanism that essential parts of the latter may be incorporated in the new design. For this purpose, in accordance with the invention, the arrangement is as follows:

Symmetrically to the central shaft *a* of the fuse there are provided a pair of centrifugal weights *b*, *b'*. The centrifugal weights are constructed in the form of toothed segments and engage with their teeth *c*, *c'* in pinions *d*, *d'*. The pinions *d*, *d'* are each firmly connected with a transmission or intermediate wheel *e*, *e'* constructed in the form of toothed segments, both of these wheels *e*, *e'* engaging with the pinion *f* on the central shaft or spindle *a* of the fuse. In accordance with the invention the operating segments and the transmission wheels are so mounted that in each case an operating segment *b*, *b'* and a transmission wheel *e*, *e'* together with pinion *d*, *d'* for the counter-segment are mounted on a common bearing bolt *g*, *g'*. These bearing bolts are constituted by threaded bolts which at the same time hold together the cover plates of the mechanism. The operating segments *b*, *b'* are mounted on bushes *h*, *h'*, which at the same time act as bearing pins for the bushes *i*, *i'*, to which there are secured in each case an intermediate segment *e*, *e'* and a pinion *d*, *d'*. To economize in space there is provided on

the central shaft *a* a central wheel *p* having inner teeth, which wheel meshes with the pinion *l* of the movement of the fuse (not shown).

The operating device acts as follows: After 5 the projectile has been fired, and after release of a desired safety means, the driving segments *b*, *b'* are rocked with their centres of gravity outwards under the action of the centrifugal force to the edge of the cover plate, and upon this 10 movement they drive by way of their teeth *c*, *c'* the pinions *d*, *d'* of the transmission wheels or intermediate segments *e*, *e'*, and these in turn drive the pinion *f* on the central shaft *a*. Owing to their segmental form and the correspondingly 15 selected position of their centres of gravity in relation to the axis of the mechanism and their own axes of rotation the intermediate segments *e*, *e'* assist the drive of the centrifugal weights *b*, *b'*. The central shaft *a* drives through 20 the medium of the central wheel *p* having the inner teeth the pinion *l* belonging to the mechanism.

The problem on which the selected embodiment is based, viz., that of doubling the period 25 of operation of an existing operating device is accordingly solved by the fact that the diameter of the pair of transmission wheels *e*, *e'* has been substantially doubled as compared with the previous diameter, which is rendered possible by 30 the embodiment of the transmission wheels in the form of toothed segments and by the particular method of mounting the same. Further it is possible considerably to increase the diameter of the central wheel by providing it with 35 inner teeth. Since on the other hand the mechanism *m* between the balance and the central wheel is to remain the same as in the case of the mechanism with half the period of operation, and accordingly the period of oscillation 40 also remains the same, the variation in the transmission between drive and mechanism to obtain an operation period of twice the duration calls for twice the operative force. The possibility of fulfilling this requirement is provided for by the fact that owing to the peculiar 45 common mounting in each case of an operating segment and an intermediate segment on a single shaft a considerable space is available for increasing the mass of the operating segment 50 and its extent of movement; further, by the fact of the embodiment of the intermediate wheels *e*, *e'* as centrifugal segments an additional driving force is obtained.

The possibility of employing the new operat-

ing means in place of existing devices leads to considerable advantages and to a simplification in the manufacture and in the maintenance of stocks, as merely one single embodiment of movement and of the parts included in the re- 5 leasing and firing means is required.

What I claim is:

1. In a time fuse, a centrally disposed fuse shaft, a pair of centrifugal members disposed symmetrically to the said shaft, and transmission members each driven by one of the said centrifugal members, the said transmission members each being mounted about the axis of rotation of the opposite centrifugal member.

2. In a time fuse, a centrally disposed fuse 15 shaft, a pair of centrifugal toothed segments disposed symmetrically to the said shaft, and transmission members each driven by one of the said toothed segments, the said transmission members each being mounted about the axis of rotation of the opposite centrifugal member.

3. In a time fuse, a centrally disposed fuse shaft, a pair of centrifugal members disposed symmetrically to the said shaft, and transmission segments each driven by one of the said 25 centrifugal members and constituting themselves centrifugal members, the said transmission segments each being mounted about the axis of rotation of the opposite centrifugal member.

4. In a time fuse, a centrally disposed fuse shaft, a pair of centrifugal members disposed symmetrically to the said shaft, a clockwork mechanism controlled by the said centrifugal members, cover plates to the said clockwork 35 mechanism, threaded bolts holding the said cover plates together, and transmission members each driven by one of the said centrifugal members, one centrifugal member and one transmission member being disposed in common on one 40 of the said bolts.

5. In a time fuse, a centrally disposed fuse shaft, a wheel having inner teeth mounted on the said shaft, a pair of centrifugal members disposed symmetrically to the said shaft, a clock- 45 work mechanism controlled by the said centrifugal members through the medium of the said shaft, and transmission members each driven by one of the said centrifugal members and engaging with the said wheel on the said shaft, the 50 said transmission members each being mounted about the axis of rotation of the opposite centrifugal member.

HELMUT JUNGHANS.
